UNITED STATES PATENT OFFICE.

FRANZ TRINKS, OF BRUNSWICK, GERMANY.

PAPER-STRIP FEED FOR ADDING-MACHINES.

1,399,450.

Specification of Letters Patent.

Patented Dec. 6, 1921.

Application filed September 8, 1916. Serial No. 119,018.

(GRANTED UNDER THE PROVISIONS OF THE ACT OF MARCH 3, 1921, 41 STAT. L., 1313.)

To all whom it may concern:

Be it known that I, FRANZ TRINKS, manufacturer, citizen of the Duchy of Brunswick, Empire of Germany, residing at 5 Brunswick, Germany, have invented certain new and useful Improvements in Paper-Strip Feeds for Adding-Machines, of which the following is a specification.

The present invention generally relates to 10 adding machines, and more particularly to an adding machine of the type in which numbers and items are set up by means of keys and transmitted into the accumulating mechanism through operation of a main 15 actuating member. In machines of this character it is usual to provide a printing mechanism in conjunction with the setting-up mechanism and the accumulator, for causing the numbers and items set up to 20 be listed on a continuous strip of paper, the transmission of the numbers and items to be printed into the printing mechanism and the actual printing being performed through operation of the main actuating member. 25 In such machines it is known to mount the platen or printing support in an oscillatory frame and to effect the printing by a short swinging movement of the platen against the printing types previously adjusted in 30 printing position. In such machines it is further known to utilize the swinging movement of the oscillatory platen frame for the purpose of advancing or feeding the revolvably mounted platen for the distance of 35 one listing line at each printing operation. It is here that my present invention comes in, its object being to provide means in conjunction with the above mentioned feeding means, whereby the platen can be caused 40 to automatically advance for the distance of two listing lines at each oscillation of the platen. It is a further object of my invention to provide means whereby both strokes of one operative oscillation of the platen 45 are simply utilized for causing an advance of the revolvble platen, the specific arrangement being such that the platen is turned or fed the distance of one listing line at the first stroke and the distance of another 50 listing line at the return stroke. A further object of my invention is to provide means whereby the improved feeding means for turning the platen double the amount of

the normal feeding distance may be rendered operative and inoperative by the operator and in accordance with requirements. 55

With these and other objects in view, my invention consists in certain structural and functional features which I will now describe with reference to the accompanying 60 drawings in which I have illustrated, by way of example, an embodiment of my invention, it being understood that modifications, such as will readily occur to those skilled in the art to which this invention 65 appertains, may be made without involving a departure from the scope of the invention.

Figure 1 shows in a side view and partly in section a machine of the type in connection with which I prefer to apply my invention; Fig. 2 being a similar view but showing parts disposed in another vertical plane and not visible in Fig. 1.

Since for my present invention the particular construction of the setting-up mechanism as well as the accumulator may be of any approved type I have refrained from illustrating such mechanism, although I prefer to apply my invention in connection with mechanisms such as I have specifically 80 described and illustrated, for instance, in my copending application Ser. No. 117,791.

Referring to Fig. 1, 6 is a circular printing type carrier supported on a transverse shaft 7 and provided upon a portion of its 85 periphery with gear teeth 23 meshing with the toothed sector 22 which is carried by a gear wheel 21 and in operative connection with the main actuating member. The circular type carrier 6 is provided with fixed 90 printing types 8 and a slidably mounted zero type 8'. When the type carrier 6 is being revolved a pivotally mounted arm 45 is caused by a cam member 44 to swing downward thereby sliding the zero type 8' 95 into operative position, the same being normally held withdrawn in a position in which no print of the zero character can be produced. On level with the printing line, the platen 1 is mounted on a transverse rod 2 100 which is carried in a frame 3 comprising two arms of which but one only is visible in Fig. 1. The frame 3 is oscillatingly mounted on pivots 4 and has a lateral extension 30, see Fig. 2, the end of which is 105 provided with a pin 31 engaging a cam

groove 32 in the face of a disk 33. The cam disk 33 is mounted on the shaft 7 mentioned above as supporting the printing type carriers 6 of which the machine contains one 5 for each denominational order. The cam disk 33 is adapted to be revolved by means of the gear wheels 52 and 51 which are operatively connected with the main actuating member of the machine and are thereby 10 actuated prior to the conclusion of the movement of the main actuating member. The cam groove 32 is of such a shape that during a part of the revolution of the cam disk 33 the platen carrying frame 3 has imparted 15 to it a short swinging movement toward the type carriers 6 whereby those of the printing type which have previously been moved into printing line are caused to be printed on a continuous strip of paper 5 which is 20 drawn from a roll 25 revolvably supported in a partly open bearing 26 formed at the upper end of each arm of the frame 3. The paper on being drawn from the roll 25, is first passed downwardly around a portion 25 of the circumference of the platen 1 and then led upwardly between a pair of guide rolls 27, 27 and then out of the machine through an opening 28 in the machine casing. Between the continuous strip of paper 30 5 and the printing types there is provided in the printing line an inking ribbon 29 which may be fed transversely through the machine by any approved mechanism known in the art. The platen 1 is provided with 35 a gear wheel 16 which meshes with another gear wheel 15. The latter wheel is mounted on a pivot 14 on the frame 3 and is fixedly connected with a ratchet wheel 10. Within the oscillatory path of the ratchet wheel 10 40 there is provided a feeding pawl 11 pivotally supported on a stationary pin 12 and subjected to the action of a spring 13 which tends to yieldingly hold the tooth 9 of the pawl 11 within the oscillatory path of the 45 ratchet wheel 10. When the frame 3 is swung rearward under the control of the cam groove 32 the ratchet wheel 10 passes over the tooth 9 of the pawl 11 without being turned by the same. At the end of the 50 oscillatory rearward stroke the tooth 9 under the action of the spring 13 engages a tooth of the ratchet wheel 10. When thereafter the oscillatory motion of the frame 3 is reversed and the latter swings toward 55 the printing type the ratchet wheel is fed for the distance of one tooth. This feeding movement is transmitted by means of gear wheels 15 and 16 to the platen 1 and, in consequence, the listing strip 5 is advanced 60 for the distance of one listing line. This is the normal operation of the carrying mechanism for the platen so far described. Now, according to my invention there is provided a second feeding pawl 17 pivotally mounted 65 on a stationary pin 19 and having a tooth 18 which projects into the oscillatory path of the ratchet wheel 10. The spring 20 corresponds in its function to the spring 13 of the oppositely disposed feeding pawl 11. The feeding pawl 17 acts similarly to the pawl 11 except that the same is operative at that stroke of the oscillatory frame 3 at which the pawl 11 is inoperative, viz. at the rearwardly directed swinging movement of the platen frame 3. The tooth 18 is shown 70 in Fig. 1 to be in position to engage the ratchet wheel 10 when the same swings rearwardly with the frame 3 whereby the ratchet wheel is advanced one step in the same direction in which the opposite pawl 11 will turn it when the frame 3 performs the reversed oscillatory stroke. Thus, at each complete oscillation of the frame 3 the ratchet wheel 10 is advanced for the distance of two teeth causing the listing strip 80 to also advance a distance corresponding to the distance of two listing lines. 85 Provision is made to render the feeding pawl 17 inoperative when it is desired to turn or feed the platen the normal distance 90 resulting in advancing the paper strip for the amount of one listing line. For that purpose the said pawl is shown to be extended so as to project through the machine casing and is provided with a handle 17' by 95 means of which it may be raised so as to move its tooth 18 out of the oscillatory path of the ratchet wheel 10. To secure the pawl 17 in each of its two positions there is provided a yielding locking pin 35 which is 100 adapted to engage notches in a laterally extending arm 34 of the said pawl 17 and is yieldingly held engaged therewith by a spring 36. The two notches of the arm 34 correspond to the two positions of the pawl 17 in which the same is either operative or inoperative. 105 When the pawl 17 is raised, the platen 1 is then advanced by the pawl 11 only, viz. one step at each printing operation. 110 What I claim as my invention and desire to secure by Letters Patent of the United States, is:—

1. In a machine of the character described, a feeding mechanism for a revoluble platen, 115 comprising in combination, an oscillatory frame adapted to support the revoluble platen, means for oscillating said frame once at each printing operation, an intermittent motion member supported on said oscillatory frame and operatively connected to said revoluble platen, a relatively stationary intermittent motion member adapted to engage and advance said first named intermittent motion member at one stroke of each oscillation 120 of said oscillatory frame, and another relatively stationary intermittent motion member adapted to engage and advance said first named intermittent motion member at a stroke opposite to said first named stroke of 130

each oscillation of said oscillatory frame, said last named member being disposed so as to advance said first named intermittent motion member in the same direction in which 5 said second named member advances said first named intermittent motion member, whereby said platen is fed two steps at each printing operation.

2. In a machine of the character described, 10 a feeding mechanism for a revoluble platen, comprising in combination, an oscillatory frame adapted to support the revoluble platen, means for oscillating said frame once at each printing operation, an intermittent 15 motion member supported on said oscillatory frame and operatively connected to said revoluble platen, a relatively stationary intermittent motion member adapted to engage and advance said first named intermittent motion member at one stroke of each oscillation of said oscillatory frame, and another relatively stationary intermittent motion member adapted to engage and advance said first named intermittent motion member at a stroke opposite to said first named stroke of each oscillation of said oscillatory frame, said last named member being disposed so as to advance said first named intermittent motion member in the same direction 25 in which said second named member advances said first named intermittent motion member, and at least one of said second and third named intermittent motion members being adapted to be rendered inoperative 30 whereby the feeding operation may be varied so as to feed the platen either one step or two steps at each printing operation.

3. In a machine of the character described, 40 a feeding mechanism for a revoluble platen, comprising in combination, an oscillatory frame adapted to support the revoluble platen, means for oscillating said frame once at each printing operation, an intermittent motion member supported on said oscillatory 45 frame, motion transmitting means between said intermittent motion member and said revoluble platen, a relatively stationary intermittent motion member adapted to engage and advance said first named intermittent motion member at one stroke of each oscillation of said oscillatory frame, another relatively stationary intermittent motion member adapted to engage and advance said first 50 named intermittent motion member at a stroke opposite to said first named stroke of each oscillation of said oscillatory frame, said last named member being disposed so as to advance said first named intermittent motion member in the same direction in which 55 said second named intermittent motion member advances said first named intermittent motion member, whereby said platen is fed two steps at each printing operation, and means for rendering at least one of said second and third named intermittent motion 60 members inoperative when the said platen is to be fed but one step at each printing operation.

4. In a machine of the character described, 65 a feeding mechanism for a revoluble platen, comprising in combination, an oscillatory frame adapted to support the revoluble platen, means for oscillating said frame once at each printing operation, a revoluble intermittent motion member supported on said oscillatory frame, motion transmitting means between said revoluble intermittent motion member and said revoluble platen, a relatively stationary intermittent motion member adapted to engage and advance said first 70 named intermittent motion member during one stroke of each oscillation of said oscillatory frame, means for yieldingly holding said second named intermittent motion member within the oscillatory path of said first named intermittent motion member, another relatively stationary intermittent motion member adapted to engage and advance said first named intermittent motion member during the opposite stroke of each oscillation 75 of said oscillatory frame, said second and third intermittent motion members being disposed relatively to each other so as to advance said first named intermittent motion member in one and the same direction, and means for yieldingly holding said last named intermittent motion member within the oscillatory path of said first named intermittent motion member, whereby said platen is fed 80 two steps at each printing operation.

5. In a machine of the character described, 85 a feeding mechanism for a revoluble platen, comprising in combination, an oscillatory frame adapted to support the revoluble platen, means for positively causing said frame to oscillate rearward and forward at each printing operation, a ratchet wheel supported on said oscillatory frame, motion transmitting means between said ratchet wheel and said revoluble platen, a relatively 90 stationary and pivotally supported member adapted to engage and advance said ratchet wheel one step at each stroke in one direction of said oscillatory frame, means for yieldingly holding said member within the oscillatory path of said ratchet wheel, another relatively stationary member adapted to engage and advance said ratchet wheel one step at each reverse stroke of said oscillatory frame, said last named member being 95 adapted to be moved into inoperative position, both of said members being disposed relatively to each other so as to advance said ratchet wheel in one and the same direction, and means for yieldingly locking said last named member in either of its two positions, whereby when said last named member is in its operative position said platen is fed two steps during each printing operation while when said last named member is in its inop- 100

erative position the normal feeding of one step is in force during each printing operation.

6. A paper strip feeding mechanism for adding machines, comprising, in combination, a revolute platen around which the strip is arranged to pass; an oscillatory frame wherein said platen is mounted; operating means for said frame; a ratchet wheel carried by said frame and geared to said platen; and a pair of oppositely-acting pawls engageable with said ratchet wheel and arranged to rotate the same solely in one direction, one pawl active during one stroke of the frame, and the other pawl during the return stroke thereof, whereby said ratchet wheel and said platen will be fed two steps at each complete oscillation of the frame.
7. In a paper strip feeding mechanism for adding machines, the combination, with a revolute platen around which the strip is arranged to pass; of an oscillatory frame; operating means for said frame; and mechanism controlled by the oscillation of said frame for feeding said platen, comprising a ratchet wheel geared to said platen, and a pair of oppositely-arranged pawls co-operative therewith, one pawl adapted to engage and rotate said ratchet wheel during one stroke of the frame, and the other pawl adapted to engage and rotate said ratchet wheel in the same direction during the return stroke of said frame.
8. In a paper strip feeding mechanism for adding machines, the combination, with a revolute platen around which the strip is arranged to pass; of an oscillatory frame; operating means for said frame; mechanism controlled by the oscillation of said frame for feeding said platen, comprising a ratchet wheel geared to said platen, and a pair of oppositely-arranged pawls co-operative therewith, one pawl adapted to engage and rotate said ratchet wheel during one stroke of the frame, and the other pawl adapted to engage and rotate said ratchet wheel in the same direction during the return stroke of said frame; and means for throwing one of said pawls out of action, whereby said ratchet wheel will be rotated during one stroke only of the frame.
9. A paper strip feeding mechanism for adding machines, comprising, in combina-

tion, a revolute platen around which the strip is arranged to pass; an oscillatory frame wherein said platen is mounted; operating means for said frame; a ratchet wheel carried by said frame and geared to said platen; a pair of oppositely-acting pawls engageable with said ratchet wheel and arranged to rotate the same solely in one direction, one pawl active during one stroke of the frame, and the other pawl during the return stroke thereof, whereby said ratchet wheel and said platen will be fed two steps at each complete oscillation of the frame; and means for throwing one of said pawls out of action.

10. In a paper strip feeding mechanism for adding machines, the combination, with a revolute platen around which the strip is arranged to pass; of an oscillatory frame; operating means for said frame; and mechanism controlled by the oscillation of said frame for feeding said platen, comprising an intermittent motion member, and a pair of oppositely-arranged actuating members therefor, one adapted to actuate said intermittent motion member during one stroke of the frame, and the other adapted to actuate said intermittent motion member in the same direction during the return stroke of the frame.

11. In a paper strip feeding mechanism for adding machines, the combination, with a revolute platen around which the strip is arranged to pass; of an oscillatory frame; operating means for said frame; mechanism controlled by the oscillation of said frame for feeding said platen, comprising an intermittent motion member and a pair of oppositely-arranged actuating members therefor, one adapted to actuate said intermittent motion member during one stroke of the frame, and the other adapted to actuate said intermittent motion member in the same direction during the return stroke of the frame; and means for throwing one of said actuating members out of action.

In testimony whereof I have hereunto set my hand in presence of two subscribing witnesses.

FRANZ TRINKS.
